UNITED STATES PATENT OFFICE.

JAMES FERRIER, OF SURAT, QUEENSLAND, AUSTRALIA.

WELL-DRILLING TOOL.

1,181,071.

Specification of Letters Patent. Patented Apr. 25, 1916.

Application filed November 10, 1915. Serial No. 60,785.

To all whom it may concern:

Be it known that I, JAMES FERRIER, a subject of the King of Great Britain and Ireland, &c., residing at Surat, in the State of 5 Queensland, Commonwealth of Australia, have invented certain new and useful Improvements in and Relating to Well-Drilling Tools; and I do hereby declare the following to be a full, clear, and exact description of the invention, such as will enable others skilled in the art to which it appertains to make and use the same.

This invention relates to percussive well drilling tools, especially the drilling bit under the sinker bar, to which also this invention 15 can be applied.

Drilling tools vibrate when jumped in a deep bore, and are apt to break the sides of the hole and cause the direction of the bore to depart from the vertical. To improve its 20 trueness the bore is, according to known methods, subsequently dressed by a reamer having a body of relatively large diameter. But by my invention I save time by producing 25 a satisfactory bore in one operation; that is a straighter bore, and it is drilled faster.

Another feature of known methods is that the drilling bit rotates somewhat to 30 strike the bottom in a new place at many of its impacts. The suspending cable connects with a swivel which permits the cable and connected tools to yield easily to any rotative influence. There is a natural tendency to rotation due to the cable very slightly stretching and untwisting its strands, owing to 35 the weight of the suspended tools and its own length, as the bit descends, and then a reaction occurs, the cable twisting in the contrary direction (but not necessarily to the 40 same extent) upon the bit reaching the bore bottom, or as it is raised. The directions of such automatic rotation depend on the direction of twist of the strands, and whenever 45 the rotation one way is unequal to that in the reverse direction the successive impacts on the bore bottom will be in different positions (in plan view) but will frequently be much less than 20 degrees away from one 50 another and some of the successive blows will occur at about the same place. The latter is a disadvantage which makes drilling slow and difficult, and which my invention avoids. I so vary the rotative effects that the angle 55 between successive impacts may approximate generally to a third or half of a right angle,

but in any case there will be much less likelihood of successive impacts coming in the same place.

In applying my invention, the drilling bit, 60 a sinker bar, or the like is made of special form, and is given any length of stroke suiting the geological formation. Known means exist to regulate the speed of the drilling bit, and for my purposes the speed of dropping it should differ from the speed of raising it, as by being faster; the extent of rotation during the drop will then differ more certainly from the extent of reverse rotation while the bit is being raised, that is any 65 tendency of the rotation to be equal each way is obviated.

The drilling bits I use have bases with edges of any known kind, and I use flat sides to allow of easy resharpening or dressing when 75 required. The cutting edge is slightly wider than the bit body which instead of being an ordinary flat bar, is a bar with a longitudinal twist of slow pitch, and small extent, comprising for example, less than one revolution. My improved tools will in practice 80 be provided in sets of different dimensions to allow drillmen to select to suit their work. To augment the rotative effect any sinker 85 bar or the like above the bit may have a similar longitudinal twist but as ordinary sinker bars are of small diameter relatively to that of the bore, a twist in an ordinary bar would have little rotative effect; therefore I use bars of enlarged diameter, though not so 90 large as to jam in the bore.

In the drawings herewith simple embodiments of this invention are illustrated.

Figure 1 shows my improved bit; and Fig. 2 shows this bit on a smaller scale attached to my improved sinker bar.

a is a cutting edge at the bit base.

b is the lower end of the bit, slightly wider than the bit body *e*. The lower part *b* has in my preferred form flat surfaces which 100 allow of easy resharpening.

c is any wrench squared upper end of the bit, and *d* any suitable coupling thread.

The important part as to this invention is the body *e* between the bit ends. This 105 body has a longitudinal twist, and its width is sufficiently great to enable the twist to be effective in causing or assisting to cause by friction with the air or any matter in the bore partial rotation of the bit in one direction when it rises and in the reverse direction when it drops.

f is a twisted body of a sinker bar, having end connecting means, as screw thread *g*. The directions of twist of the parts *e* and *f*, or like tools, will be the direction 5 of twist of the cable strands, so that as the cable rotates in descending the rotation is augmented by the twist in the said tool or tools.

As those skilled in well sinking know, bits 10 and sinker bars are used with drilling jars and so forth connected between them and the cable which is reciprocated. Sometimes water is fed into the bore, the tools used being adapted to allow of water reaching the 15 bottom. I may also use water and drill jars.

Various known boring tools have twisted bodies not for the purpose of my invention, but, by rotation under force, to cause penetration 20 without reciprocation.

Having described this invention what is claimed by Letters Patent is:—

1. In an apparatus for bore drilling by percussion, an elongated tool having a wide 25 body thin in cross section and twisted from a point substantially adjacent its cutting edge to a point substantially adjacent its upper end, the cutting edge of the tool being wider than the twisted body, whereby the 30 sides and edges of said twisted portion will be free of contact with adjacent parts of the apparatus and the walls of the bore, the twisted portion of the body in its movement acting against the air or any matter in the 35 well, causing rotation of the tool as the latter rises and falls.

2. In an apparatus for bore drilling by

percussion, an elongated tool having a wide body thin in cross section and twisted from a point substantially adjacent its cutting 40 edge to a point substantially adjacent its upper end, a sinker bar having a wide body thin in cross section and connected to the tool and provided with a twist corresponding to the twist of the tool, the twist in the 45 sinker bar extending substantially throughout its entire length, the cutting edge of the tool being wider than the twisted body, whereby the edges of the twisted portions of the tool and the sinker bar will be free 50 of contact with adjacent parts of the apparatus and the walls of the bore, the twisted portions of the tool and the sinker bar when the latter are raised and lowered being acted on by the air or other matter in the bore will 55 cause rotation of said tool and sinker bar.

3. In an apparatus for bore drilling by percussion, an elongated tool having a wide body of less width than the width of the cutting edge, said body being thin in cross 60 section and twisted substantially throughout its length, the body of the tool being of less width than the cutting edge the sides and edges of said twisted portion will be free of contact with adjacent parts of the 65 apparatus and the walls of the bore when the tool is in operation, the twisted portion of the body in its movement acting against the air or any matter in the well, causing rotation of the tool as the latter rises and 70 falls.

In witness whereof I have hereunto set my hand.

JAMES FERRIER.
